CLAIM

The ornamental design for a toy vehicle restraint system, as shown and described.

DESCRIPTION

FIG. 1 is a front perspective view showing my new design, the broken line showing the toy vehicle in FIGS. 1 and 2 is for illustrative purposes only and forms no part of the claimed design;

FIG. 2 is a rear perspective view thereof;

FIG. 3 is a left side elevational view thereof, the side opposite being a mirror image;

FIG. 4 is a top plan view thereof;

FIG. 5 is a rear elevational view thereof;

FIG. 6 is a front elevational view thereof;

FIG. 7 is a front perspective view showing a second embodiment of the new design, the broken line showing of the toy vehicle in FIGS. 7 and 8 is for illustrative purposes only and forms no part of the claimed design;

FIG. 8 is a rear perspective view of the second embodiment;

FIG. 9 is a left side elevational view of the second embodiment, the side opposite being a mirror image;

FIG. 10 is a top plan view of the second embodiment;

FIG. 11 is a rear elevational view of the second embodiment; and,

FIG. 12 is a front elevational view of the second embodiment.

The bottom view of the design is devoid of ornamentation.
